UNITED STATES PATENT OFFICE.

JAMES L. SHANNON, OF SPRINGFIELD, MASSACHUSETTS.

SPRING CONTACT FOR FLASH LIGHTS.

Application filed March 30, 1926. Serial No. 98,464.

This invention relates to improvements in flashlight constructions and particularly to that part of the light which pertains to the mounting of the bulb, and the cushion 5 contact construction between one terminal of the battery and the terminal of the lamp.

An object of the invention is to provide a cushioning device between the lamp terminal and the battery terminal for the purpose of preventing the breakage of the lamp when the battery is inserted or accidentally dropped into the casing. Heretofore breakages of the bulb often occur when the battery is inserted or should the lamp be accidentally dropped.

A further object of the invention is to provide a structure for attaching the yieldable or cushioning contact member of a cup shaped member, which carries the bulb in order that the battery cushioning member may be retained in place. This construction broadly comprises a rectangular shaped opening in the bottom of the cup shaped member to receive a correspondingly shaped rivet which passes through insulating washers having rectangular shaped openings and a rectangular shaped opening in the cushioning member whereby when the rivet is headed over all possibility of the cushioning device becoming misplaced is thoroughly prevented.

Referring to the drawings:

Fig. 1 is a detail sectional view of one end of a flash light showing the bulb, the cup shaped member for receiving the socket for the bulb, the cushioning device which is attached to the bottom of the cup shaped member and with which one terminal of the battery contacts, also the lens and the deflector member.

Fig. 2 is a bottom plan view of the cup shaped member removed from the battery casing part of the lamp showing the rectangular shaped rivet construction which secures the cushioning contact device to the member.

Fig. 3 is a top plan view of the inside of the cup shaped member and the socket for receiving the bulb and the inner end of the riveting device.

Fig. 4 is a sectional view of the cup shaped member through the rectangular rivet opening.

Fig. 5 is a detail view of the lamp socket which is located in an opening of the cup shaped member.

Fig. 6 is a sectional view of the ring of insulating material which fits over the lamp socket.

Fig. 7 is a detail view of the contact spring 60 which is attached to the bottom of the cup for forming a cushion and terminal support for the battery.

Fig. 8 is a detail view of one of the washers of insulating material with the rectangular shaped opening.

Fig. 9 is a detail view of the rivet, and

Fig. 10 is a sectional view of a modification.

Referring to the drawings in detail:

1 designates the barrel or casing portion of the flash light which is usually composed of suitable insulating material as hard fiber. 2 designates the battery having the terminal 3. Located on the outer end of the casing is 75 a cup shaped member 4 having the bottom portion 5, the side portion 6 and flange 7, the flange 7 rests upon the outer end of the casing 1 and the reflector 8 which is of metal rests upon the flange 7 whereby an electric 80 contact is provided through the cup shaped member 4 to the ground or other terminal of the battery. The other terminal of the battery being indicated at 3. 11 designates a V-shaped or bent contact piece of phosphor 85 spring bronze having a rectangular opening 12 and a bent or off set portion 13 and recess 13' with which the terminal 3 of the battery 2 engages, as shown in Fig. 1. The bottom 5 of the cup shaped member 4 is 90 formed with a rectangular shaped opening 14. 15 are the two washers of insulating material that are located on the opposite sides of the bottom part of the metallic cup shaped member. These washers are also 95 formed with a rectangular shaped opening 16. 17 designates a rectangular shaped metallic rivet which is passed through the rectangular shaped openings just referred to, whereby when the parts and the rivet are 100 assembled and the rivet headed over the member 11 said parts will be prevented from turning or becoming displaced relative to the axis of the casing. 18 designates a sleeve or washer member of insulating material 105 which is slipped over the metal socket 9 and within the neck portion 19 of the reflector 8. When the battery 2 is inserted the terminal 3 engages the spring contact strip 13, and being of elastic or springy material it 110 absorbs or cushions the fall of the battery thus preventing the breakage of the electric

bulb 20 which is often the case in the present flash light construction when the battery is inserted.

It will be seen from this description that 5 the cup shaped member 4 is provided with a battery cushioning device and a rectangular rivet construction which maintains the contact member always in place in the axial line and at the same time prevents the 10 breakage of the bulbs. Also, that the cup shaped member may be readily removed and replaced when desired. 21 designates the usual metallic head piece which is secured to the casing 1 and formed with a thread 15 to receive the thread bezel ring 22 that retains the lens 23 in place.

The bottom 5 of the cup shaped member 4 is formed with an opening 5' which receives the socket member 9 and the flange 20 10 is located on the inner surface of the bottom 5.

Referring to the construction shown in Fig. 10. 24 designates a casing member which is formed of metal instead of fibre 25 as shown in Fig. 1. The cup shaped member 25 is formed with its edge slightly flattened as indicated at 27 in Figs. 2, 3, and 4 in order that it may be inserted in the hook 30 or bent over end 28 of the metallic strip 29 which extends along the inside of the metal casing 24, and is insulated from the casing 24 by means of the insulation 30. A suitable switch, not shown, is understood to be included in the strip 29. Located between 35 the metal casing 24 and the metallic strip 29 and the side 6 of the metallic cup shaped member 25 is a sleeve of insulating material 30'. 31 is a ring or gasket of insulating material which rests upon the upper end of the 40 metal casing 24 and the upper edge of the metal cup 25 and insulates the cup from the casing. The circuit through the lamp is as follows; battery terminal 3, to the depression 13' in strip 13, through the lamp filament, socket 9, cup 5, strip 29 to the other 45 terminal of the battery.

What I claim is:

1. In a flashlight construction, in combination with a battery inclosing member, a 50 reflector member, a metallic cup shaped member formed with a flange portion which is located between the end of the battery inclosing member and the reflector member for engaging one end of the casing and the 55 reflector member, said cup shaped member having a battery contacting cushioning device attached to its metallic bottom portion, means for attaching the cushioning device to the cup shaped member to prevent its 60 being moved out of its normal position relative to the axial line of the casing, said cushioning device being substantially V-

shaped with one portion of which serves as a battery terminal contact and the other as a lamp terminal contact.

2. A metallic cup shaped member for 65 flashlight having an opening to receive a lamp socket in its bottom portion and a rectangular shaped rivet receiving opening, a battery cushioning and contact device 70 formed with a rectangular shaped opening, insulating washers located on the opposite sides of the bottom of the cup shaped member and formed with rectangular shaped openings, the contact device being located on 75 the lower insulating washer, whereby when a rectangular shaped rivet is inserted through the said rectangular shaped openings and headed over, the cushioning and contact device is prevented from being displaced by turning on the rivet as a center.

3. In a flashlight construction, in combination with a battery inclosing casing, a metallic cup shaped member located in the outer end of the casing, a reflector member 85 having an opening, a threaded lamp socket in the opening, a bulb located in the socket, the threads of the socket serving for attaching the socket receiving bulb in the opening of the reflector, a battery cushioning and terminal device substantially V-shaped and having one end attached to and below the bottom of the cup shaped member by means of a rectangular shaped rivet and its other end being formed with a depression which 90 is in engagement with the terminal of the battery.

4. A flashlight construction comprising in combination, a battery casing, a cup shaped member located in one end and closely fitting the interior of the casing, conducting material between the cup shaped member and a terminal of the battery, and electrically connected to the cup shaped member, a V-shaped spring contact terminal attached 100 to the said cup with which one terminal of a battery engages, and having a depression therein for engaging said terminal and an electric bulb mounted in the cup shaped member.

5. A flashlight construction comprising a battery inclosing casing, a metallic cup shaped member insertable in and filling an end of the casing, a V-shaped cushion spring battery and lamp terminal contact 115 device attached to the said cup member and insulated therefrom and having a depression therein for receiving a battery terminal, a lamp socket on the cup shaped member, an electric bulb attached to the said socket of 120 the cup shaped member, a battery, and conducting means between the cup shaped member and the other terminal of the battery.

JAMES L. SHANNON.
